US0D1106387S

(12) **United States Design Patent** (10) **Patent No.:** **US D1,106,387 S**
(45) **Date of Patent:** **** Dec. 16, 2025**

(54) **FUEL FILTER**

(71) Applicant: **Costex Corporation**, Miami, FL (US)

(72) Inventors: **Alice Diaz**, Miami, FL (US); **Gabriel Martos**, Miami, FL (US); **Danny Varona**, Miami, FL (US)

(73) Assignee: **Costex Corporation**, Miami, FL (US)

(**) Term: **15 Years**

(21) Appl. No.: **29/930,425**

(22) Filed: **Feb. 29, 2024**

(51) LOC (15) Cl. **12-16**

(52) U.S. Cl.

USPC **D12/197**; D15/5; D23/209

(58) **Field of Classification Search**
